(57) **CLAIM**

The ornamental design for a heat press machine, as shown and described.

DESCRIPTION

FIG. 1 is a perspective view of a heat press machine, showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the heat press machine in a configuration of use;

FIG. 10 is an enlarged view of portion 10 shown in FIG. 1; and,

FIG. 11 is an enlarged view of portion 11 shown in FIG. 2. The broken lines in the drawings depict portions of the heat press machine that form no part of the claimed design. The dash dot broken lines on FIGS. 1, 2, 10 and 11 are provided to define the enlargement regions in each and form no part of the claimed design.

1 Claim, 11 Drawing Sheets
